UNITED STATES PATENT OFFICE.

AARON S. NEWMARK, OF BROOKLYN, NEW YORK, ASSIGNOR, BY DIRECT AND MESNE ASSIGNMENTS, TO JOSEPH EISNER AND JOSEPH I. LUBIN, BOTH OF NEW YORK, N. Y.

WINDOW CORNICE.

Application filed October 31, 1927. Serial No. 230,148.

This invention relates to ornamental window cornices for the interior decoration of windows and for use in connection with window draperies, hangings, curtains and the like.

5 The invention broadly comprehends an improved cornice which is capable of a wide range of adjustment to conform to the variation in the width of windows with which the same may be associated.

10 The invention further comprehends an adjustable window cornice of the character set forth which is readily, easily and accurately adjustable and which is provided with means for effectually retaining the adjustment.

15 The invention furthermore embodies in an adjustable window cornice, novel supporting brackets therefor which are designed to support drapery or curtain poles in addition to the cornice.

20 As a further object the invention comprehends a graduated scale forming a part of the window cornice and by virtue of which the cornice may be adjusted to conform to the distance between the supporting brackets which have been previously applied and measured so that the operation of mounting the cornice on the brackets is simplified.

25 More specifically the invention comprehends an adjustable cornice including telescopically associated sections equipped with means for preventing complete separation and which are so constructed as to allow for collapsing or telescoping of the same to a minimum length for transportation or storage.

30 Other objects reside in the simplicity of construction, the economy with which the same may be produced and the general efficiency derived therefrom.

35 With the above recited and other objects in view, reference is had to the following description and accompanying drawings in which there is exhibited one example or embodiment of the invention, while the appended claims define the actual scope of the invention.

40 In the drawings—

45 Figure 1 is a front view of the cornice in applied position;

Fig. 2 is a plan view thereof;

Fig. 3 is a rear face view of the cornice;

Fig. 4 is an enlarged front view of the cornice with parts shown in section and taken 50 approximately on the line 4—4 of Fig. 5;

Fig. 5 is a fragmentary sectional view taken approximately on the line 5—5 of Fig. 4;

Fig. 6 is a further enlarged sectional view taken approximately on the line 6—6 of Fig. 5;

Fig. 7 is a sectional view taken approximately on the line 7—7 of Fig. 5;

Fig. 8 is a fragmentary enlarged sectional view taken approximately on the line 8—8 of Fig. 4.

Referring to the drawings by characters of reference, the cornice includes an intermediate section 10 and end sections 11 and 12. The intermediate section is of substantially channel-shape in cross section and is preferably of sheet metal including a rear wall 13 and upper and lower forwardly projected flanges 14 and 15. A front wall 16 is positioned between the free edges of the forwardly projecting flanges and said front wall is preferably of wood which is anchored in place by means of nails, screws, or other fastening devices 17 which are driven through the flanges 14 and 15 and anchored into the front wall 16. The front wall or panel 16 may be suitably ornamented or decorated with marginal strips 18 to give the desired decorative effect. From this construction it will be seen that the intermediate cornice section is of substantially tubular configuration in cross section.

The end sections 11 and 12 which are of substantially identical construction are preferably composed of a sheet metal channel-shaped element having a front wall 19 and upper and lower flanges 20 and 21 which extend rearwardly from the front wall and which are provided with inwardly bent terminals 22 and 23 disposed in parallel relation to the front wall 19. Preferably the terminals are doubled upon themselves to increase their rigidity for a purpose to be hereinafter set forth. Suitably decorated marginal strips 24 are attached to the front face 80 of the front wall 19 of end sections 11 and 12, said marginal strips conforming to the marginal strips 18 of the intermediate section to carry out the decorative scheme. The cross-sectional size of the end strips is such 85 that the same may be telescopically associated with the intermediate section for relative adjustment of the end sections with respect to the intermediate section so that the length of the cornice may be increased or decreased to 90

conform to variations in the width of the windows to which the same is applied.

In order to secure the end sections in relatively adjusted relation to the intermediate section, clamping means carried by the intermediate section are employed, and said clamping means consists of an internal plate 25 disposed within the inner surface of the rear wall 13 adjacent each end of the intermediate section. The clamping plate is provided with forwardly projecting upper and lower marginal flanges 26 and 27 which engage the inside faces of the flanges 20 and 21 of the end sections and serve to unite them in their adjusting movement, in addition to rendering additional strength for the clamping action. The clamping means further includes outer cross bars 28 disposed in rear of the rear wall 13. A bolt including a threaded shank 29 having a head 30 at its inner end, extends through aligned apertures in the plate 25, the wall 13 and the cross bar 28, and the rearwardly projecting outer end of the shank has a thumb nut 31 engaged thereover. The terminals 22 and 23 of the end sections 11 and 12 are engaged and slidably between the flanged marginal edges of the clamping plates 25 and the rear wall 13 of the intermediate section so that tightening of the thumb nut 31 frictionally clamps the terminals 22 of the end section flanges against relative sliding movement of the end sections with respect to the intermediate section.

One of the distinctive features of the invention resides in the provision of the means for clamping the end sections 11 and 12 to the intermediate section 10, as above indicated. That is to say, since the front faces of both the intermediate section and the end sections are usually ornamented or decorated, provision must be made for effecting adjustment between the sections in such a way that relative movement therebetween will not mar or efface the decoration on the front of the end sections. To that end, as clearly shown in Figs. 5 and 6 of the drawings, the front surfaces of the end sections 11 and 12 are maintained out of contact with the inside face of the intermediate section 10 through the medium of the novel clamping plates 25 and their associated parts. In connection with these plates 25, it is pointed out that the same are anchored by the screws 25^a to the back 13 of the intermediate section 10. Therefore, each plate is intended to assume a fixed position at the end of the intermediate section.

The screw 25^a connects the plate with the rear wall 13 in such a way that due to the inherent resiliency of the plate 25 the end sections may be moved when the locking means 28-29-30-31 is released. However, when the nut of the locking means is tightened up the parts are securely held in their adjusted position.

From the foregoing it will not only be

apparent that the plate 25 provides means for holding the sections in such relation that they may be moved without scratching the faces of the end sections, but also, since the plate 25 is of substantially rectangular formation and the fastenings 25^a and 30 are in alinement, relative twisting or canting of the end sections with reference to the intermediate section is prevented. In other words, the plates 25 act as guides for the end sections, and are an important feature in a construction of this kind not only because they facilitate adjustment, but also because they prevent sagging of the intermediate section under its own or assumed weight if used on long spans. 80

Also, it may be pointed out that the present construction avoids the use of a fastening between the end sections and the intermediate section corresponding to a set screw which would have the effect of forcing the ornamental faces of the end sections into engagement with the inside face of the intermediate section which is an undesirable feature for the reasons heretofore indicated. 85

In order to facilitate accurate and corresponding adjustment of the end sections with respect to the intermediate section, graduated scales 32 either directly inscribed on the rear surface of the walls 19 of the end sections or on a gage strip 33 secured thereto, are employed. These scales will include indicia 34 by virtue of which the actual measurement of the length of the cornice may be determined after the adjustment has been made. 90

In order to prevent complete separation of the end sections from the intermediate section, the innermost ends of the end sections have attached to the rear surface of their walls 19, a transverse limiting strip 35 which is adapted to abut with the flanges 26 and 27 of the clamping plates 25. The free outer ends of the end sections 11 are directed rearwardly or bent to dispose the terminals 36 thereof at a right angle to the remainder of the sections and in order to reinforce the terminals 36, the flanged terminals 22 and 23 at this point are rolled about reinforcing wires 37. 100

The supporting brackets for the cornices are composed of a strip of material bent and formed to provide a base 38 having forwardly projecting upper and lower arms 39 and 40. The upper arm of each bracket is slotted or bifurcated at 41 and is of a width to snugly fit between the rolled flanged terminals 22 and 23 and the wall 19. The upper flange 20 of the terminal has extending through an aperture therein, a bolt 42 having a thumb nut 43 which secures the cornice to the bracket. The lower arm 40 of each bracket has an upturned inner marginal flange 44 having curtain or drapery supporting notches 45 extending downwardly from the upper edge. The base 38 is provided with apertures 46 through which screws, nails, or other attaching devices 47 are passed for anchorage in the window frame F. In in-

stances where it is desired to attach the bracket to the inner side edge S of the window frame, the base 38 is provided with a right-angularly disposed forwardly projecting attaching 5 flange 48 which is apertured at 49.

In practice, the brackets are attached to the window frame at the desired point, after which the space between the brackets is measured. With this measurement obtained, the 10 user adjusts the end sections 11 correspondingly to the reading of the scales 32, the cornice terminals 36 may then be slipped over the brackets and clamped in place by the bolts and thumb nuts 42 and 43.

15 What is claimed is:

1. A window cornice, including an intermediate tubular section and channel-shaped end sections telescopically associated therewith and having longitudinally extending 20 flange terminals, means carried by the intermediate section for clamping engagement with the flange terminals to retain the sections in relatively adjusted relation, the said end sections each having its free outer end directed rearwardly, brackets over which said ends are engaged, said brackets consisting of a base and forwardly projecting upper and lower arms, the former arm being slotted, and means carried by the rearwardly directed 25 ends of the end sections for clamping the same to the slotted bracket arms.

2. A window cornice, including an intermediate tubular section and channel-shaped end sections telescopically associated therewith and having longitudinally extending 35 flange terminals, means carried by the intermediate section for clamping engagement with the flange terminals to retain the sections in relatively adjusted relation, the said end sections each having its free outer end directed rearwardly, brackets over which said ends are engaged, said brackets consisting of a base and forwardly projecting upper and lower arms, the former arm being slotted, and 40 means carried by the rearwardly directed ends of the end sections for clamping the same to the slotted bracket arms, the remaining lower arms of the brackets having an up-standing notched flange for receiving and 45 holding curtain or drapery poles.

3. A window cornice construction including a tubular intermediate section, end sections telescopically interfitting therewith, and means for guiding the end sections in their 55 movement with reference to the intermediate section, and maintaining the front faces of the end sections out of contact with the inside face of the front wall of the intermediate section.

60 4. A window cornice construction including a tubular intermediate section, end sections adapted to telescopically interfit with the intermediate section, and means for maintaining said end sections in adjusted relation 65 with reference to the intermediate section,

said means including a member for holding the end sections in engagement with the rear face of the intermediate tubular section, whereby the front faces of the end sections will be spaced from the inner face of the intermediate section. 70

5. A window cornice construction including a tubular intermediate section, channel-shaped end sections telescopically associated therewith, a fastening and adjusting unit carried by the rear wall of the intermediate section and including a plate member adapted to have a normally frictional engagement with the end sections and serving to hold the end sections spaced from the inner face of the intermediate section, and locking means for clamping the plate member in engagement with the end sections. 75

6. A window cornice construction including a tubular intermediate section and end sections telescopically associated therewith, a clamping device carried by the rear wall of the intermediate section and having means for maintaining the end sections out of engagement with the inside face of the front wall of the tubular section, and means for adjusting and locking said end sections with reference to the intermediate section. 80

7. A window cornice construction including a tubular intermediate section, channel-shaped end sections telescopically interfitting with the said intermediate section, a clamping device carried by the rear wall of the intermediate section and comprising a resilient plate having offset flanges adapted to engage within the channel-shaped end sections to guide the same in their movement, and means for placing said resilient plate under compression to lock the end sections in their adjusted position. 95

8. A window cornice construction including a tubular intermediate section, channel-shaped end sections telescopically interfitting with the said intermediate section, a clamping device carried by the rear wall of the intermediate section and comprising a resilient plate having offset flanges adapted to engage within the channel-shaped end sections to guide the same in their movement, and means for placing said resilient plate under compression to lock the end sections in their adjusted position, said means comprising a screw engaging the body of the plate and having the threaded shank projecting through the rear wall of the intermediate section, an elongated spring washer arranged transversely of the outside of the rear wall of the intermediate section, and a clamping nut carried by said threaded shank of the screw for engaging said washer. 100
